V. GIOVAGNONI

Des. 158,740

NEGLIGEE

Filed Feb. 4, 1950

FIG. 1

FIG. 2

VIOLET GIOVAGNONI, INVENTOR.
BY Louis Casper
attorney

Patented May 30, 1950

Des. 158,740

UNITED STATES PATENT OFFICE

158,740

NEGLIGEE

Violet Giovagnoni, New York, N. Y.

Application February 4, 1950, Serial No. 7,730

Term of patent 7 years

(Cl. D3—26)

To all whom it may concern:

Be it known, that I, Violet Giovagnoni, a citizen of the United States, residing in New York city, in the county of New York and State of New York, have invented a new, original, and ornamental Design for a Neglige, of which the following is a specification, reference being had to the accompanying drawing, forming part thereof.

Fig. 1 is a front view of a neglige, showing my design, and

Fig. 2 is the rear view thereof.

I claim:

The ornamental design for a neglige, substantially as shown.

VIOLET GIOVAGNONI.

No references cited.
